PACKAGING CUP FOR FOOD OR THE LIKE

Odo Klose, Wuppertal-Elberfeld, Germany, assignor to
Fritz Meckenstock, Wuppertal-Elberfeld, Germany

Filed Nov. 2, 1970, Ser. No. 25,786

Claims priority, application Germany May 2, 1970

Term of patent 14 years

Int. Cl. D9—03

U.S. Cl. D9—220

FIG. 1

FIG. 2

FIG. 1 is an elevational view of a packaging cup for food or the like, showing my new design;

FIG. 2 is a top plan view thereof; and

FIG. 3 is a section along the line 3—3 of FIG. 1.

I claim:

The ornamental design for a packaging cup for food or the like, as shown.
